UNITED STATES PATENT OFFICE.

JOHN F. O'CONNOR, OF CHICAGO, ILLINOIS, ASSIGNOR TO WILLIAM H. MINER, OF CHAZY, NEW YORK.

DRAW-BAR AND DRAFT-YOKE CONNECTING MEANS IN RAILWAY-CAR DRAFT-RIGGING.

1,220,536.

Specification of Letters Patent. Patented Mar. 27, 1917.

Application filed July 26, 1916. Serial No. 111,365.

To all whom it may concern:

Be it known that I, JOHN F. O'CONNOR, a citizen of the United States, residing at Chicago, in the county of Cook and State 5 of Illinois, have invented a certain new and useful Improvement in Draw-Bar and Draft-Yoke Connecting Means in Railway-Car Draft-Rigging, of which the following is a full, clear, concise, and exact description, 10 reference being had to the accompanying drawings; forming a part of this specification.

My invention relates to improvements in draw bar and draft yoke connecting means 15 in railway car draft rigging.

One of the objects of my invention is to provide an efficient means for connecting a draft yoke and a draw bar in draft rigging for railway cars. Other objects will appear 20 from the description of my invention herein following.

In the drawings forming a part of this specification, Figure 1 is a side elevation, partly in vertical longitudinal section, of a 25 draw bar and draft yoke embodying my invention. Fig. 2 is a horizontal section taken on line 2—2 of Fig. 1. Fig. 3 is a cross section taken on line 3—3 of Fig. 1.

Referring to the drawings, the numeral 4 30 designates a draw bar, having the usual butt 5 and the upper and lower shoulders 6 and 7, respectively. The draft yoke is indicated by the numeral 9, the said yoke having an upper limb 10, a lower limb 11, a rear connecting member 12 and a hollow head 13, which is preferably integral with the said limbs. Within the head is provided an upper gib 14, adapted to engage the upper shoulder 6 of the draw bar and the lower 35 portion of the head is provided with a draw bar locking lever 15, which is provided with a shoulder 16 adapted to engage the lower shoulder 7 of the draw bar when the draw bar locking lever is in locking position, as 40 illustrated in Fig. 1 of the drawings. The said lever is swingingly connected at its rear end 17 to the yoke, as for instance by the hinge member 18, including the pin 19 and the cotter 20, which, with the head 21 thereof, prevents the accidental displacement 45 of the said pin.

The arm 21 of the draw bar locking lever 50 is forwardly extended along the under-face 22 of the draw bar, and in preferable 55 construction is of substantially the same

width as the draw bar, the forward end 23 of said lever being sufficiently extended to permit the said lever to ride between the draw bar 14 and the draw bar carry iron 24, which is secured by suitable means, such as bolts 25, to parts of the car above the draw bar, as for instance the buffer block 26. Other parts of a car underframe, as the end sill and center sills, are not shown in the drawings, but the functions of my invention 60 will, nevertheless, be readily understood.

In assembling the draw bar with the yoke, when the yoke is in its position upon the car, the draw bar is shoved rearwardly within the head of the yoke, sliding upon the 70 face 27 of the rear portion of the lever, which is in a plane angular to the axis of the draw bar in locked position, but which in its unlocked position is parallel thereto, and assumes the position indicated by the 75 dotted lines at 28 in Fig. 1 of the drawing, during the insertion of the draw bar within the yoke head. It will be understood that the space between the face 27 of the lever 15 and the lower face of the gib 14 of the yoke 80 is sufficient to permit the rearward passage of the butt 5 of the draw bar 4 therethrough. When the draw bar has been forced rearward sufficiently to aline the upper shoulder 6 rearwardly of the gib 14, the 85 draw bar locking lever is then pulled upwardly, the said lever serving to lift the draw bar until the upper shoulder 6 thereof is in engagement with the gib 14 of the yoke, whereupon the shoulder 16, provided 90 upon the lever, will be in engagement with the lower shoulder 7 of the draw bar, and the arm 21 of the lever will be extended along the under face 22 of the draw bar 4. The draw bar carry iron is then placed in 95 position and secured in the usual manner by the bolts 25. It will thus be apparent that the draw bar locking lever not only serves the function of lifting the draw bar into its engaging position within the yoke and 100 also serves as a lock to secure the draw bar thereon, but that it also provides a wear plate underneath the draw bar to prevent the usual extensive wear of the draw bar occasioned by its reciprocating movements 105 upon the draw bar carry iron and that the said lever 21, upon becoming sufficiently worn, may be readily replaced by the substitution of a new lever, thus obviating the great expense attendant upon replacing 110

draw bars rendered unsafe or brought to destruction through wear.

From an inspection of Fig. 1, it will be noted that the position of the lever 15 indicated by dotted lines, is determined or limited by the lower horizontal wall of the hood. In this open position, the extension 21 is inclined forwardly and downwardly, thus providing an incline to facilitate insertion of the draw bar and to act as a guide in pushing the draw bar butt within the yoke. It is evident that the yoke itself will be supported by the gear when the draw bar is being inserted or removed.

15 I claim:

1. A yoke for draft riggings having means at its forward end for coöperation with the upper shoulder of a draw bar, said yoke having a displaceable locking member 20 adapted to coöperate with the lower shoulder of a draw bar when the locking member is in operative position, said member having a forward extension and the yoke having means to limit the degree of displacement of 25 said member from operative position, whereby said member is positioned with its exten-

sion extending forwardly and downwardly to thereby facilitate insertion of a draw bar within the yoke.

2. A yoke for draft riggings having a 30 hood at the forward end thereof, the upper wall of the hood having a shoulder arranged to coöperate with the upper shoulder of a draw bar, said hood having a locking member pivotally mounted therein at the bottom, 35 said member having a shoulder arranged to coöperate with the lower shoulder of the draw bar, said locking member having also a forwardly extended arm, the lower wall of the hood limiting the downward movement of the locking member to thereby position said arm so as to extend forwardly and downwardly to thereby facilitate insertion of a draw bar within the hood. 40

In witness that I claim the foregoing I 45 have hereunto subscribed my name this 22nd day of July 1916.

JOHN F. O'CONNOR.
